Primary Examiner — Ian Simmons*Assistant Examiner* — Samantha Q Lawrence(74) *Attorney, Agent, or Firm* — Panitch Schwarze Belisario & Nadel LLP(57) **CLAIM**

The ornamental design for a solar canopy, as shown and described.

DESCRIPTION

FIG. 1 is a top perspective view of a solar canopy showing our new design;

FIG. 2 is a front elevational view thereof;

FIG. 3 is a rear elevational view thereof;

FIG. 4 is a right side elevational view thereof;

FIG. 5 is a left side elevational view thereof; and,

FIG. 6 is a top plan view thereof.

The broken lines in the figures illustrate portions of the solar canopy that form no part of the claimed design.

The solar canopy is shown with symbolic break lines in its length, width and height. The appearance of any portion of the solar canopy between the break lines forms no part of the claimed design.
